UNITED STATES PATENT OFFICE.

PHINEAS B. MYERS, OF NEW YORK, N. Y.

DESIGN FOR A PAPER BOX.

SPECIFICATION forming part of Design No. 32,611, dated May 1, 1900.

Application filed April 6, 1900. Serial No. 11,898. Term of patent 7 years.

To all whom it may concern:

Be it known that I, PHINEAS B. MYERS, a citizen of the United States, and a resident of New York, (Brooklyn,) county of Kings, and State of New York, have invented a new and original Design for a Paper Box, of which the following is a specification, reference being had to the accompanying drawings, in which—

Figure 1 is a perspective view of a paper box, showing my new design; and Fig. 2 is a vertical section on line 2 2, Fig. 1.

As shown in the drawings, the leading feature of my design consists of a paper box made in the shape of a house A, upon the

gable roof *a* of which a sleigh *b*, drawn by ¹⁵ reindeers *c*, is represented. On top of the chimney *d* is perched the figure of Santa Claus *e*. The blinds *f* of one of the windows are open to expose an interior mantel *g*.

What I claim is—

The design for a paper box, substantially as herein shown and described.

Signed by me at New York city, county and State of New York, this 5th day of April, 1900.

PHINEAS B. MYERS.
